(57) **CLAIM**

The ornamental design of a kiosk, substantially as shown and described.

DESCRIPTION

FIG. 1 is a front perspective view of a kiosk showing our new design;

FIG. 2 is a front view thereof;

FIG. 3 is a rear view thereof;

FIG. 4 is a right side view thereof (the left side view is the same as the right side view);

FIG. 5 is a top view thereof; and,

FIG. 6 is a bottom view thereof.

The broken lines are included for the purpose of illustrating the unclaimed portions of the article and form no part of the claim.

1 Claim, 5 Drawing Sheets
